UNITED STATES PATENT OFFICE.

GUSTAV MEZ, OF BADEN, GERMANY.

LETTER-FILE AND THE LIKE.

No. 822,147.

Specification of Letters Patent.

Patented May 29, 1906.

Application filed September 5, 1905. Serial No. 277,078.

To all whom it may concern:

Be it known that I, GUSTAV MEZ, factory manager, a subject of the German Emperor, residing at 20 Lichtenaler Alle, Baden, 5 Grand Duchy of Baden, in the Empire of Germany, have invented certain new and useful Improvements in Letter-Files and the Like, of which the following is a specification.

The present invention has for its object a 10 top bar for files for letters and the like, which is broadly characterized by the fact that the lateral edges of this bar are turned over upwardly throughout its entire length, so as to form slots or grooves in which one or 15 more slides are guided. This formation is especially applicable to cases in which two slides are used, because the outer positions of the slides may be limited in a very simple manner by providing the grooves with simple indentations at the desired places, and thereby limiting the path of the slides. A 20 particularly advantageous construction is one in which the interval between these limiting indentations and the perforations through 25 which the binding-bands pass in the bar is such that in their extreme outer position the slides uncover the openings, so that the binding-bands may be turned over either inwardly or outwardly, as desired. Although 30 the formation of the grooves strengthens the bar, if desired, it may be still further strengthened by providing it with a middle longitudinal rib.

Figure 1 of the accompanying drawings 35 shows this novel top bar in perspective at the moment at which it is being passed upon the binding-strips *a a*, which in the present case are assumed to be fixed upon the fold *f* of a file *y*. They may, however, be fixed upon 40 the cover of the file itself. Fig. 2 shows the top bar with the slides *e e* pushed outward with the binding-strips turned down outward. Fig. 3 shows the top bar in side elevation. Fig. 4 represents the slides *e e* in 45 their end position with the binding-strips turned down inward. Fig. 5 shows the manner in which the slides retain the inwardly-bent strips. Fig. 6 is a cross-section through the bar on the line A B of Fig. 2 when no middle rib is formed, and Fig. 7 is a similar section with strengthening-ribs.

In the top bar represented in the drawings 50 its outer edges are bent over upwardly in such a manner that they form grooves in which the two slides *e e* are able to slide to and fro. Their extreme outer position is de-

fined by indentations *d d* in the grooves *c*. As shown in Figs. 2 and 4, the position of these indentations is selected in such a manner relatively to the length of the slides that when these latter occupy their outermost position either the whole of the openings *g* or a portion of them are uncovered, so that the binding-strips may be inserted, as shown in Fig. 4.

If it is desired to turn the binding-strips down outwardly, in the first place the slides are arranged in the middle, as shown in Fig. 1. If, on the contrary, it is desired to turn the binders down inwardly, the slides are 75 first arranged in the position shown in Fig. 4.

The advantages of the invention reside in the fact that, owing to the turning over of its edges the top bar of the file is considerably strengthened throughout its entire length. 75 Top bars for files of the usual kind—that is to say, those in which no such stiffening is provided upon their outer ends—present the defect, if they are of any considerable length, of readily bending at the ends, so that they hold down the edge of the letters or the like imperfectly. It is, however, of great importance that the edge should be held down, the middle portion of the letters being secured by the binders, while the outer ends depend upon the bar for their retention. This effect is still further increased if the bar is made of the cross-section shown in Fig. 7—that is to say, is formed with a middle rib *r*. In most cases, however, a rectilinear cross-section, such as illustrated in Fig. 6, is sufficient. The further advantage is secured that the slides cannot possibly tear the letters beneath them in their displacement. The indentations in the grooves constitute an exceedingly simple means for limiting the displacement of the slides.

The form of the slides and their length may vary as desired. If it is desired to limit the displacement of the slides toward the middle, this may likewise be effected by means of indentations.

What I claim, and desire to secure by Letters Patent of the United States, is—

1. In a top bar for files such as described, a sheet-metal strip having perforations, the lateral edges of said bar being turned upward and over to form grooves, and slides held in the grooves and between the turned edges to slide over the perforations.

2. In a top bar for files such as described, a perforated sheet-metal strip having its lat-

eral edges turned upward and over to form grooves, slides held in said grooves and indentations in the overturned edges to limit the movement of the slides.

- 5 3. In a top bar for files such as described, a sheet-metal strip having perforations and upwardly-overturned edges to form lateral grooves, and a rib formed on its bottom, in combination with slides extending between and held in said grooves, substantially as described.
4. In a top bar for files such as described, a sheet-metal strip having perforations, upwardly-overturned edges to form lateral

grooves and a medial depressed rib, depressions in the overturned edges and slides mounted between the overturned edges in the grooves formed thereby to slide over the perforations, said depressions in the edges acting as stops to limit the movement of the slides.

In testimony whereof I have hereunto set my hand, in presence of two subscribing witnesses, this 1st day of August, 1905.

GUSTAV MEZ.
